UNITED STATES PATENT OFFICE.

HOWARD F. MARSTON AND JOHN J. O'CONNELL, OF DAYTON, OHIO.

WINDOW-ENVELOP.

1,202,401.

Specification of Letters Patent. Patented Oct. 24, 1916.

Application filed July 16, 1915. Serial No. 40,196.

To all whom it may concern:

Be it known that we, HOWARD F. MARSTON and JOHN J. O'CONNELL, citizens of the United States, residing at Dayton, Ohio, 5 have invented certain new and useful Improvements in Window-Envelops, of which the following is a full, clear, and exact description.

This invention relates to certain new and 10 useful improvements in envelops of the type known as window or outlook envelops.

One object of this invention is to so fabricate the envelop blank that the amount of 15 paper wasted is minimized. In this way the price of the envelop is reduced.

Another object of our invention is to place the patch in a novel position on the blank which position facilitates the applying of the patch.

20 Another object of our invention is to produce an envelop in which the front of the envelop is open while the inclosure is being inserted so that the inscription on the inclosure will be visible to the person inserting 25 the inclosure in the envelop. With this construction, the person inserting the inclosure is less liable to make mistakes such as placing the letter or the inclosure in the envelop upside down or wrong side forward.

30 In the drawings: Figure 1 shows the envelop blank with the transparent patch attached, and with the flaps gummed and ready for folding. Fig. 2 shows the envelop folded and ready for the inclosure. Fig. 3 35 shows the envelop with the inclosure therein, and with the seal flap folded down.

The body portion of the envelop is made of opaque material. This opaque portion of the blank comprises the blank shown at 40 10 and defined by fold lines 11, 12, 13 and 14; second, the side flaps 15 and 16 defined by fold lines 11, 13 and margins 17 and 19; third, the body flap 25 defined by fold line 14 and margin line 24; fourth, the seal flap 45 20 defined by fold line 12 and margin line 18. The seal flap is gummed as shown by the shaded gum strips 33. The bottom flap is also gummed as shown by the shaded gum spots 34. It will be understood that if desired 50 the gum spots 34 can be placed on the side flaps 15 and 16 instead of on the bottom flap 25. When this is done, the side flaps are first folded and the bottom flap is folded 55 over them instead of vice versa as is the case with the construction illustrated in Figs. 1 and 2. The seal flap 20, defined by lines 21,

18, 23, and fold line 12, has a window aperture 30 cut therein. This aperture 30 is defined by the line 31. Over this aperture is placed a transparent patch 27. Transparent 60 patch 27 is secured by gum to the border of the aperture 30. The transparent patch terminates at the line 32 as shown in Figs. 1 and 2. It will be understood that this patch 27 is applied over the window before the envelop is folded and before the gum strip 33 is applied to the seal flap 20.

In making the envelop the body portion is cut to the shape shown in Fig. 1, and the patch 27 is applied as previously explained. 70 Then, gum is applied to the blank at the points indicated by the shaded portions 33 and 34. Thereafter, the side flaps 15 and 16 are infolded, and finally the bottom flap 25 is folded over and engaged by the gum spots 75 34 to the bottoms of the side flaps.

The completed envelop ready for the inclosure is shown in Fig. 2. In this figure it will be seen that the side flaps 15 and 16, when infolded, form edge supports for the 80 inclosure while the bottom flap 25 forms a bottom support for the said inclosure. Since the side flaps 15 and 16, when infolded, terminate at a distance from each other, the front of the envelop is left entirely open 85 with the exception of a small part about the border. This allows the person inserting the inclosure in the envelop to at all times see the inscription on the inclosure, and in this way prevent mistakes in placing 90 the inclosure in the envelop. After the inclosure is correctly inserted in the envelop, the seal flap is folded down and engaged by the gum portion 33 to the side and bottom flaps 15, 16 and 25. The sealed envelop is 95 shown in Fig. 3.

It is to be understood that we do not wish to be limited to the precise form and construction shown in the drawings and described in the specification, since other modifications will occur to those skilled in the art. What we claim as our invention is particularly pointed out in the appended claims.

We claim:

1. An envelop comprising in combination, 105 an opaque body portion comprising a back portion; side flaps extending therefrom; a bottom flap; a seal flap, said seal flap having a window aperture therein; and a transparent sheet secured to the seal flap and covering the aforesaid aperture, the said seal flap engaging the side and bottom flaps and 110

forming the front of the envelop when sealed.

2. An envelop comprising in combination, an opaque back portion; side and bottom flaps extending therefrom, said flaps engaging each other and thereby forming edge supports for the inclosure; a seal flap engaging said side and bottom flaps to close the envelop, said seal flap having a window aperture therein; a transparent sheet engaged by the seal flap and covering the aforesaid aperture.

3. An envelop comprising in combination, an opaque back portion; a bottom flap; a pair of side flaps infolded and engaging the bottom flap at their ends, said side flaps, when infolded, being spaced from each other whereby the inscription on the inclosure is visible when the said inclosure is being inserted in the envelop; and a seal flap folding over and engaging the said side flaps and the bottom flap and thereby forming the front of the envelop, the said seal flap having a window aperture therein.

4. An envelop comprising in combination, an opaque back portion; a bottom flap, a pair of side flaps infolding and engaging the bottom flap at their ends; said side flaps, when infolded, being spaced from each other whereby the inscription on an inclosure is visible when the said inclosure is being inserted in the envelop; and a seal flap folded over and engaging the said side flaps and the bottom flap and thereby forming the front of the envelop, said seal flap having a window aperture therein; and a transparent sheet secured to the seal flap and covering the aperture.

5. An envelop comprising in combination, an opaque back portion; a bottom flap; a pair of side flaps, said side and bottom flaps engaging each other and forming an envelop pocket with a substantial open face whereby the inscription on the inclosure will be visible while the inclosure is being inserted in the envelop pocket, a seal flap folded over and engaging the side flaps and bottom flaps, and thereby forming the front of the envelop, said flaps having a window aperture therein, and a transparent patch covering the aforesaid aperture.

6. An envelop comprising, in combination, an opaque back portion, an opaque bottom flap integral with and extending from the back portion, a pair of opaque side flaps integral with the back portion infolding and engaging the bottom flap at their ends, said side flaps when infolded being spaced from each other whereby the inscription on the inclosure is visible when the said inclosure is being inserted in the envelop; an opaque seal flap integral with the back portion and perforated with a window aperture, said seal flap being adapted to fold over and engage the side and bottom flaps and thereby form the front of an envelop, and a transparent sheet covering said window and secured by gum to the borders of the window.

In testimony whereof we affix our signatures in the presence of two subscribing witnesses.
